UNITED STATES PATENT OFFICE.

JAMES M. FAIR, OF NARBERTH, PENNSYLVANIA.

RAIL-ANCHOR.

1,364,263.

Specification of Letters Patent.

Patented Jan. 4, 1921.

Application filed August 19, 1920. Serial No. 404,605.

To all whom it may concern:

Be it known that I, JAMES M. FAIR, a citizen of the United States, residing at Narberth, in the county of Montgomery and 5 State of Pennsylvania, have invented certain new and useful Improvements in Rail-Anchors, of which the following is a specification.

This invention relates to improvements in 10 rail anchors adapted to be applied to railroad rails for the purpose of engaging stationary parts of the road bed to prevent longitudinal displacement or creeping of the rails over the supports therefor.

15 The object of the invention is to provide a novel, simple and efficient anchor formed of a single piece of metal which may be readily applied to a railroad rail and which will be held in operative position thereon by 20 the tendency of the anchor to resume a condition from which it was sprung when applied to the rail, and which will effectually grip the rail and coöperate with a stationary part of the road bed to prevent the rail from 25 creeping when in service.

With the above and related objects in view, the invention consists in the novel construction, combination and arrangement of parts hereinafter described and claimed.

30 In the accompanying drawings, illustrating my invention,

Figure 1 is a plan view of a portion of a railroad rail, a cross tie supporting the same and a rail anchor applied to the rail, showing one form of embodiment of my invention.

Fig. 2 is a side view thereof.

Fig. 3 is a vertical section, on line 3—3 of Fig. 1.

40 Fig. 4 is a sectional detail through the rail anchor and a part of the rail base, on line 4—4 of Fig. 3.

Fig. 5 is a view showing one position of the rail anchor relatively to the rail while 45 it is being applied thereto.

Referring to the drawings, 2 designates a railroad rail and 5 an underlying cross-tie forming a stationary part of the road bed and supporting the rail 2 and over which the 50 rail tends to creep forwardly or in the direction of the arrow in Fig. 1 under the well known conditions.

My improved rail anchor 6 is applied to the base 7 of the rail 2 and it is formed of a 55 single piece or bar of steel or other suitable metal, preferably rectangular in cross-sec-

tion, and bent into the form shown in the drawings.

The anchor 6 thus formed and applied to the rail 2 comprises a straight or substantially straight bar 8 engaging the bottom of the rail base 7 and extending transversely beneath the same in parallel relation thereto, an arm 9 extending upwardly from one end of the bar 8 and inwardly over one side of the rail base 7, and a projection 10 on the other end of the bar 8 and extending upwardly therefrom a slight distance above the bottom of the rail base.

The free end portion of the arm 9 is engaged with the top of the rail base 7 inwardly from the edge thereof, and the remaining portion of the arm 9 is out of engagement and preferably out of contact with the top of the rail base, as clearly 75 shown in Fig. 3.

In the normal condition of the anchor 6, before being applied to the rail 2, the distance between the top of the bar 8 and the bottom of that part of the arm 9 which is engaged with the top of the rail base 7 is less than that shown in Fig. 3 or less than the thickness of that part of the rail base 7 which is between them, and the bar 8 and arm 9 are sprung apart when the anchor is 85 applied to the rail so that the anchor in tending to resume its normal condition presses the top of the bar 8 up against the bottom of the rail base 7 and the bottom of the arm 9 down upon the top of the rail 90 base by the resilient action of the metal forming the anchor, and thereby causes the anchor 6 to firmly grip one side of the rail base.

The accidental displacement of the anchor 95 6 in a direction which would move the arm 9 outwardly from its gripping position and thereby loosen the same is prevented by the projection 10 which rests adjacent to the opposite edge of the rail base 7 and is adapted 100 to engage the same for that purpose.

In applying the anchor 6 to the rail 2, the anchor is first placed in the position relatively to the rail as shown in Fig. 5. In this position, the extreme free end of the arm 9 is engaged with the top of the rail base 7, at 11, the top of the bar 8 is engaged with the bottom of the rail base 7, at 12, and the top of the projection 10 is engaged with the bottom of the rail base 7, at 13. After 110 the anchor 6 is thus placed, it is driven on to the rail 2 in the direction of the arrow

in Fig. 5. As the anchor is thus driven on to the rail, the free end portion of the arm 9 and the bar 8 are sprung apart due to the horizontal bottom face of the rail base 7 and the upwardly inclined face of the side thereof engaged by the arm 9. As the anchor is driven in the direction of the arrow, the pressure at the points 11, 12 and 13 of the arm 9, bar 8 and projection 10 increases until just before the inner face of the projection 10 comes into registry with the edge of the adjacent side of the rail base, so that when such registry occurs the resiliency of the metal forming the anchor will cause the full length of the bar 8 beneath the rail base 7 to be snapped up into engagement therewith and into parallel relation with the bottom thereof, as the anchor reaches its final position, as shown in Fig. 3. Therefore, it will be understood that, after the anchor reaches its final position, the projection 10, engaging the adjacent edge of the rail base, will effectually prevent accidental displacement of the anchor from the rail because it will be necessary to spring the arm 9 and bar 8 apart in order to lower the top of the projection 10 into the plane of the bottom of the rail base 7 which is necessary for the removal of the anchor from the rail. Should it be desired to remove the anchor 6 from the rail 2, the same may be done by driving the projection 10 and the adjacent end of the bar 8 downwardly, and driving the entire anchor in a reverse direction to that described for applying it to the rail. After the projection 10 moves up to the position shown in Fig. 3, after applying the anchor to the rail, as above described, the distance between the top of the bar 8 and the free end portion of the arm 9 is greater than in the normal condition of the anchor before being applied to the rail, so that, as the anchor tends to resume its normal condition, its resilient action presses the bar 8 firmly up against the bottom of the rail base 7 and the free end portion of the arm 9 firmly down upon the top of the rail base 7 and firmly grips the rail base between them. The anchor 6 is driven on to the rail 2 adjacent to a cross-tie 5, as shown in Figs. 1, 2 and 3, and, thereafter, as the rail 2 tends to creep forwardly or in the direction of the arrow in Fig. 1, the bar 8 will engage the cross-tie 5 and prevent the creeping of the rail, due to the grip of the anchor 6 upon the rail base 7. As the rail 2 tends to creep, it presses the bar 8 against the cross-tie 5 and thereby tends to tilt the anchor in a manner to throw the bar 8 thereof rearwardly and the arm 9 thereof forwardly. This action tends to force the arm 9 downwardly into firmer gripping engagement with the top of the rail base 7, and to force the bar 8 upwardly into firmer gripping engagement with the bottom of the rail base,

so that the gripping engagement of the anchor with the rail will be increased by and in proportion to the pressure of the forces tending to cause the rail to creep.

The metal bar forming the anchor 6 is bent, as clearly shown in Figs. 1 and 2, to deflect the arm 9 laterally of the bar 8 from a position directly above the same and in a direction reversely to that indicated by the arrow in Fig. 1 in which the rail tends to creep. The purpose of this is to bring the lower forward edge 14 of the arm 9 closer to a position directly above the upper rearward edge 15 of the bar 8. As the tendency of the anchor to tilt, under the tendency of the rail to creep, as just described, tends to obliterate the gripping action of the anchor upon the rail at the corners 16 and 17 of the arm 9 and bar 8, respectively, and tends to increase the gripping action at the corners 14 and 15, I obtain greater leverage and more efficient action by deflecting the arm 9, as above described, than would be obtained if the arm 9 were not deflected and the corners 14 and 16 of the arm 9 were directly over the corners 17 and 15, respectively, of the bar 8.

While the top of the bar 8 is engaged with the bottom of the rail base 7 throughout the width of the rail base, the greatest pressure of the bar against the bottom of the rail base occurs at that portion of the bar 8 which is engaged with the rail base 7 directly beneath the free end portion of the arm 9 which is engaged with the top of the rail base, or that portion of the bar 8 which engages the rail base with the arm 9 in a vertical plane which extends parallel to the longitudinal center of the rail 2 and which is indicated by the line 4—4 hereinbefore referred to.

I claim as my invention:—

1. The combination with a railroad rail, of a rail anchor comprising a substantially straight bar engaging the bottom of the rail base and extending transversely beneath the same in parallel relation thereto, an arm extending upwardly from one end of the bar and inwardly over one side of the rail base and having its free end portion engaged with the top of the rail base and the remaining portion thereof out of engagement with the top of the rail base, and a projection on the other end of the bar extending above the bottom of the rail base adjacent to and adapted to engage the edge of the other side of the rail base, said anchor in tending to resume a condition from which it was sprung when applied to the rail base causing said bar to exert an upward pressure against the bottom of the rail base, and said arm to exert a downward pressure against the top of the rail base.

2. The combination with a railroad rail, of a rail anchor comprising a bar extending

- transversely beneath the rail base and engaging the bottom thereof, an arm extending upwardly from one end of the bar and inwardly over one side of the rail base and engaging the top thereof, and a projection on the other end of the bar extending above the bottom of the rail base adjacent to and adapted to engage the edge of the other side of the rail base, said bar and said arm en-
- 5 gaging the bottom and the top of the rail base, respectively, at points in a vertical plane which extends parallel to the longitudinal center of the rail and being pressed into engagement therewith by said anchor
- 10 15 in tending to resume a condition from which it was sprung when it was applied to the rail.
3. The combination with a railroad rail, of a rail anchor formed of a single piece of metal and comprising a bar extending transversely beneath the rail base and engaging the bottom thereof, an arm extending upwardly from one end of the bar and inwardly over one side of the rail base and
- 20 25 30 35 engaging the top thereof, and a projection adapted to engage the other side of the rail base to prevent outward displacement of said arm, said bar and said arm being pressed into engagement with the rail base by said anchor in tending to resume a condition from which it was sprung when it was applied to the rail and the downward pressure of said arm against the top of the rail base being resisted wholly by the upward pressure of said bar against the bottom of the rail base.
4. The combination with a railroad rail, of a rail anchor formed of a single piece of metal of substantially uniform cross-section throughout its length and comprising a bar extending transversely beneath the rail base and engaging the bottom thereof, an arm extending upwardly from one end of the bar and inwardly over one side of the rail base
- 40 and inwardly over one side of the rail base and engaging the top thereof, and a projection adapted to engage the other side of the rail base to prevent outward displacement of said arm, said bar and said arm engaging the bottom and the top of the rail base, respectively, at points in a vertical plane which extends parallel to the longitudinal center of the rail and being pressed into engagement therewith by said anchor in tending to resume a condition from which it was sprung when it was applied to the rail, and said arm being deflected laterally of the bar from a position above the same in a direction reversely to that in which the rail tends to creep.
5. The combination with a railroad rail, of a rail anchor formed of a single piece of metal of substantially uniform cross-section throughout its length and comprising a bar extending transversely beneath the rail base and engaging the bottom thereof, an arm extending upwardly from one end of the bar and inwardly over one side of the rail base and having its free end portion engaged with the top of the rail base and the remaining portion thereof out of engagement with the top of the rail base, and a projection adapted to engage the other side of the rail base to prevent outward displacement of said arm, said bar and said arm engaging the bottom and the top of the rail base, respectively, at points in a vertical plane which extends parallel to the longitudinal center of the rail and being pressed into engagement therewith by said anchor in tending to resume a condition from which it was sprung when it was applied to the rail, and said arm being deflected laterally of the bar from a position above the same in a direction reversely to that in which the rail tends to creep.
- In testimony whereof I affix my signature hereto.

JAMES M. FAIR.
